UNITED STATES PATENT OFFICE.

FREDERIC AUMONIER, OF LONDON, ENGLAND.

DESIGN FOR WALL-PAPER.

SPECIFICATION forming part of Design No. 22,801, dated September 26, 1893.

Application filed August 28, 1893. Serial No. 484,262. Term of patent 3½ years. Patented in England March 3, 1893, No. 208,528.

To all whom it may concern:

Be it known that I, FREDERIC AUMONIER, (trading as WM. WOOLLAMS & Co.,) a subject of the Queen of Great Britain, and a resident 5 of 110 High Street, near Manchester Square, London, England, have invented a new and useful Design for Wall-Paper, (patented in Great Britain on the 3d day of March, 1893, No. 208,528,) of which the following is a specification.

This design of wall paper as represented on the annexed drawing, consists of acanthus and tulips, the acanthus being arranged in wavy formation with leaves emanating from

the wavy stem and with branches having 15 leaves curved somewhat like the letter **S** tulips hanging from the stem and branches by stalks as fillings in the wider openings of the **S** like formation.

I claim—

The design for wall paper substantially as herein shown and described.

FREDERIC AUMONIER.
